UNITED STATES PATENT OFFICE

FLORENCE N. LEWIS, OF NEW YORK, N. Y.

FITTED TRAVELING BAG

Application filed December 16, 1930. Serial No. 502,632.

The object of the present invention is to provide a fitted traveling bag or "motor bag" of novel construction, it comprising a rounded stiffened upper member and parallel end side members to which a handle is attached, the upper member carrying a suspended division wall which forms a back piece for two opposed compartments the top member overhanging each compartment.

- 10 The end members are connected by a piece extending over the base or bottom of the bag, the connection with the end members ending at or above their longitudinal centre, the said piece however, at each side of the bag, extending upwardly to a point where it may be engaged by one or more straps having means such as snap fasteners to hold the piece in position so as to close the compartment which it faces. At each side of the bag, said piece when detached from its fastener may be dropped downward to expose the compartment. One of the pieces at its normally free section and on its inner face supports a mirror. Toilet or other articles such as a ticket or card case or purse may be supported in pockets or loops carried by the division wall, or one of the compartments may serve to enclose a folder having loops for carrying bottles and jars containing cosmetics as shown in the accompanying drawings.

The invention will be described with reference to the accompanying drawings in which

- 15 Fig. 1 is a view in elevation of a bag embodying the invention showing one face thereof, the cover being partly broken away to expose a folder within the adjacent compartment.

- 20 Fig. 2 is a view in elevation of the reverse side of the bag showing the cover at that side dropped downward to expose the adjacent compartment carrying pockets for the reception of a small case and a purse, the cover member carrying a mirror.

25 Fig. 3 is a side elevation of the bag in closed position.

30 Fig. 4 is a transverse sectional view on the line 4—4, Fig. 1.

35 Fig. 5 is a view similar to Fig. 3 showing

the fastener device raised and the cover members partially outward.

Fig. 6 is a fragmentary horizontal section on the line 6—6, Fig. 1.

Fig. 7 is a view of the toilet case in open position one flap thereof being partly broken away.

Referring to the drawings, it will be seen that the case comprises a stiffened curved top 1 to which is suspended as by stitching the member or members, in this case two, forming a division wall. The division wall members indicated at 2 and 3 are stitched to the top member each near an outer margin of the latter and are then brought together and each is stitched at 4 to a lining member 5.

To the top curved member 1 at each end thereof is secured an end member 6. Covering the base of the bag between two end members is a piece which has an extension at each face of the bag and which serves as a cover member for that face to enclose the space between the division wall A formed by members 2 and 3. The said piece is generally indicated at B; at each face of the bag it is stitched to the opposite end member 6 for a portion of the length of the latter. It then extends upwardly to approximately a margin of top member 1. Between the stitches and the top member 1 the piece is free so that it may be folded back to expose the compartment bounded by the division wall A. I will hereinafter term one free piece as cover 8 and the opposite free piece as cover 9.

Cover 8 has secured thereto a mirror 10. The member 8 is adapted to be secured in position by a ball and socket device. In this embodiment the socket member 11 is carried by strap 12 secured to the top piece of the bag and the ball member 13 is carried by the cover member. In the drawings I have indicated that two of said securing means are employed one near each end of the bag. Cover member 9 likewise has ball and socket connection with one or more straps 12x.

The division wall facing cover member 8 may carry a loop or pocket 14 to receive a purse 15 and a second loop or pocket 16 to receive a small case 17. On the opposite

side of the division wall the compartment facing cover member 9 may be utilized to receive a folder for toilet articles. In this embodiment the folder comprises a relatively stiff base 18 having a plurality of loops 19 each of which is adapted to hold in position a bottle or jar or other container for cosmetic or toilet accessories. The base member may be closed by the flaps 20.

10 Each of the end pieces may be provided with loops 21 to receive the end of the strap 22 the central portion of the strap forming a handle 22a by means of which the bag may be carried.

15 Having described my invention, what I claim and desire to secure by Letters Patent is as follows:—

1. A traveling and motor bag comprising a stiffened top member, a vertical division wall secured to and suspended by said top member, end members secured to the top member, a base closing member secured to each end member at the base thereof and thence extending upwardly opposite each 25 face of the division wall and continuing until each of the opposite ends of said base covering member lies adjacent one marginal edge of the top member to form a cover section for a compartment inwardly bounded 30 by said division wall, and bounded at the top by the overhanging top member and bounded at the bottom by said base closing member, an upper portion of the cover section at each side of the bag being unattached 35 to the end members so that the unattached portion may be folded down to expose the said compartment, and means for removably securing each of said unattached portions to the top member.

40 2. A traveling and motor bag comprising a stiffened top member, a vertical division wall secured to and suspended by said top member, end members secured to the top member, flexible cover for each side of the bag 45 each cover being secured to the opposed end members along the lower portion of each side edge of the cover and thence extending unattached until its upper end lies adjacent one marginal edge of the top member, so 50 that the unattached portion of the cover may be folded down to expose a compartment bounded by the end members, the overhanging portion of the top member and the cover, and means for removably securing each of 55 the covers to the top member comprising straps secured to the top member and interlocking fastening devices carried by the straps and the covers whereby when the said interlocking members are detached, the portion of each cover unattached to the end members may drop down to expose the compartment.

60 3. A traveling or motor bag comprising a curved stiffened top member, a vertical division wall secured to said top member,

end members secured to the top member, a flexible cover for each side of the bag each cover being secured to the opposed end members along the lower portion of each side edge of the cover and thence extending unattached until its upper end lies adjacent one marginal edge of the top member, so that the unattached portion of the cover may be folded down to expose a compartment, means for removably securing each of the covers to the top member, and pockets carried by the division wall.

70 In testimony whereof, I have signed my name to this specification.
